(57) **CLAIM**

The ornamental design for a shower caddy, as shown and described.

DESCRIPTION

FIG. 1 is a first perspective view of the first embodiment of a shower caddy showing my new design;

FIG. 2 is a second perspective view of the first embodiment thereof;

FIG. 3 is a front view of the first embodiment thereof;

FIG. 4 is a back view of the first embodiment thereof;

FIG. 5 is a left side view of the first embodiment thereof;

FIG. 6 is a right side view of the first embodiment thereof;

FIG. 7 is a top view of the first embodiment thereof;

FIG. 8 is a bottom view of the first embodiment thereof;

FIG. 9 is an opening state of the first embodiment of the shower caddy thereof;

FIG. 10 is an enlarged view of the selected portion 10 in FIG. 1;

FIG. 11 is a first perspective view of the second embodiment of a shower caddy showing my new design;

FIG. 12 is a second perspective view of the second embodiment thereof;

FIG. 13 is a front view of the second embodiment thereof;

FIG. 14 is a back view of the second embodiment thereof;

FIG. 15 is a left side view of the second embodiment thereof;

FIG. 16 is a right side view of the second embodiment thereof;

FIG. 17 is a top view of the second embodiment thereof;

FIG. 18 is a bottom view of the second embodiment thereof;

FIG. 19 is an opening state of the second embodiment of the shower caddy thereof;

FIG. 20 is an enlarged view of the selected portion 20 in FIG. 11;

FIG. 21 is a first, perspective view of the third embodiment of a shower caddy showing my new design;

FIG. 22 is a second perspective view of the third embodiment thereof;

FIG. 23 is a front view of the third embodiment thereof;

FIG. 24 is a back view of the third embodiment thereof;

FIG. 25 is a left side view of the third embodiment thereof;

FIG. 26 is a right side view of the third embodiment thereof;

FIG. 27 is a top view of the third embodiment thereof;

FIG. 28 is a bottom view of the third embodiment thereof;

FIG. 29 is an opening state of the third embodiment of the shower caddy thereof; and,

FIG. 30 is an enlarged view of the selected portion 30 in FIG. 21.

(Continued)

The broken lines shown in the drawings depict portions of the shower caddy that form no part of the claimed design.
